UNITED STATES PATENT OFFICE.

THOMAS M. FRANCIS AND CHARLES B. GRIFFITH, OF CARTHAGE, ILLINOIS.

DESIGN FOR A MEMBER FOR TOOLS.

SPECIFICATION forming part of Design No. 31,487, dated September 5, 1899.

Application filed July 13, 1899. Serial No. 723,743. Term of patent 7 years.

To all whom it may concern:

Be it known that we, THOMAS M. FRANCIS and CHARLES B. GRIFFITH, citizens of the United States, residing at Carthage, in the county of Hancock and State of Illinois, have invented and produced a new and original Design for a Member for Tools, of which the following is a specification.

The invention relates to a new and original design for a member of a tool, and it has for its object to provide a design of this character which will be both ornamental and useful.

The essential feature of the design resides in a bar or member provided with a claw and having a jaw, the said claw extending from the inner portion of the jaw and having a curved outer portion diverging from the outer portion of the said jaw.

The figure of the drawing is a perspective view of a bar or member, showing our new and original design.

Referring to the drawing, 1 designates a

bar or member provided at one end with a curved jaw 2 and having a claw 3 extending outward from the inner portion of the jaw 2. The claw 3 consists of a shank 4 and a curved outer portion 5. The shank 4, which is slightly curved, diverges from the jaw 2, and the curved outer portion or head 5 of the claw extends in the opposite direction from the outer portion of the jaw 2. The bar or member is provided at a point between its ends with a curved recess 6.

What is claimed is—

The design for a member of a tool, herein shown and described.

In testimony that we claim the foregoing as our own we have hereto affixed our signatures in the presence of two witnesses.

THOMAS M. FRANCIS.
CHARLES B. GRIFFITH.
